US00D371515S

United States Patent [19]

Iwaki et al.

[11] Patent Number: Des. 371,515

[45] Date of Patent: **Jul. 9, 1996

[54] **REMOTE STATION UNIT FOR GEOPHYSICAL DATA ACQUISITION AND PROCESSING SYSTEM**

[75] Inventors: **Yumio Iwaki**, Odawara; **Yoshihiro Sekino**, Ichihara; **Yoshitaka Watanabe**, Nagareyama, all of Japan

[73] Assignee: **Japex Geoscience Institute, Inc.**, Tokyo, Japan

[**] Term: 14 Years

[21] Appl. No.: 32,273

[22] Filed: Dec. 2, 1994

[30] Foreign Application Priority Data

Jun. 3, 1994 [JP] Japan 6-16281

[57] CLAIM

The ornamental design for a remote station unit for geophysical data acquisition and processing system, as shown and described.

DESCRIPTION

FIG. 1 is a top plan view of a remote station unit for geophysical data acquisition and processing system showing my new design;

FIG. 2 is a front elevational view thereof;

FIG. 3 is a rear elevational view thereof;

FIG. 4 is a bottom plan view thereof;

FIG. 5 is a right side elevational view thereof, a left side elevational view being a mirror image thereof; and,

FIG. 6 is a front, top and left side perspective view thereof.
